STOPPING MECHANISM

Fred C. Wallace, New York, N. Y., assignor to
 Federal Telephone and Radio Corporation,
 New York, N. Y., a corporation of Delaware

Application March 9, 1946, Serial No. 653,262

4 Claims. (Cl. 192—2)

1

This invention relates to mechanisms for effecting the stoppage of motor-driven devices and, more particularly, to mechanisms for effecting stoppage of such devices in a given rotary position.

In certain electric motor operated apparatus, it is sometimes desirable to effect stoppage of the apparatus in a given rotary position. Mechanisms designed for this purpose, available in the past, have been frequently inadequate insofar as they were not effective in producing positive stoppage at a given rotary point or in that they frequently caused undesired stoppage due to an inherent tendency.

It is an object of the present invention to provide a mechanism which will enable a rotatable driven apparatus to be stopped in a given rotary position.

It is another object to provide a mechanism of the type referred to which will provide for a positive stopping action.

It is still another object to provide a stopping mechanism which is substantially effective to cause stoppage at desired times only.

In accordance with the invention, the apparatus normally driven in a predetermined direction by some driving means such as electric motor is provided on the driving shaft with a stopping mechanism, including a rotary detent element which is adapted to be engaged by a stopping element arranged for separate rotary motion with respect to the drive shaft. The rotary member is adjustable in its rotary position so that the stopping means may become effective in any desired position.

The stopping element or elements are joined for operation by means of linkage provided for that purpose which at the same time is effective in controlling the drive of the shaft, for example, by controlling the power supply to the driving motor in such a way as to produce a slowdown and reversal thereof. In accordance with another feature of the invention, a portion of the detent element is arranged in such a way as to be centrifugally affected in its position by the speed of rotation whereby its becomes increasingly effective as a detent as the speed is reduced.

According to still another feature of the invention, the detent member is shaped such as to be of minimum stopping effectiveness during the forward rotation of the shaft and assuming a maximum effectiveness as the rotation of the shaft is reversed.

These and other features and objects will be more clearly understood and other features and

2

objects may become apparent from the following detailed description of this invention, reference being had to the drawings, in which:

Fig. 1 is an illustration in schematic form of a motor and a stopping mechanism in accordance with the invention; and

Fig. 2 is a view in illustration of a stopping mechanism which is an alternative of the one illustrated in Fig. 1.

Referring to Fig. 1 of the attached drawings, there is shown an electric motor 1 for driving an apparatus (which has not been shown) and which may for instance be the tuning condenser of a radio communications receiver as may be the case in scanning reception. The motor includes a field winding 2 and an armature 3. The field winding 2 is connected across a suitable power supply which is available at terminals 4 and 5. The armature 3 is normally connected to the power supply over a resistance 6 forming a portion of a voltage divider 7 connected across the line. The power supply to the armature is controlled by means of a make-and-break switch 8, including contacts 9 and 10. Contacts 9 and 10 when moved from their normal positions as indicated will effect a reversal in the polarity of the power supply with respect to the armature and at the same time an additional resistance 11 is put in circuit to provide a reduced armature voltage. The above described motor also includes make-and-break contact points 12, 13, 14 and 15. The contacts 9 and 10 are mechanically linked to a manually operable lever 16 through linkage 17, whereby they may be moved from one position to the other by operation of the lever 16.

The motor 1, for driving its load such as the tuning element of a scanning receiver, as suggested above, is provided with a shaft 18, which is also arranged to drive a stopping mechanism 19 in the direction of the arrow shown thereon. Rotatably mounted on a pivot 20 on the member 19 is a lever type member 21 having a stopping surface 22 on one side and a weighted portion 23 on the other side of the pivot. It will be apparent that the pivoted lever 21 will be subject to centrifugal action as the motor rotates the means 19 to cause the portion 23 and with it the lever 21 to assume the position shown in full line from the position indicated in broken lines at 24 into which it is normally urged by means of a leaf spring 25 secured between the means 19 and the lever 21. In order to effect the stopping of the shaft 18 a comparatively large gear 26 has been provided adjacent to means 19 and having secured thereon two stopping blocks 27 and 28.

These blocks 27 and 28 are connected to suitable linkage 29 which is turn is directly connected to the lever 16 referred to hereinabove for simultaneous radial movement of the blocks 27 and 28 with respect to the gear 26 and the shaft 18. It is thus possible to place one or the other of these blocks in contact with the surface 22. The gear 26 may be rotated, for instance, manually by means of a knob 30 on a shaft 31 through the medium of a driving gear 32 in mesh with the teeth of the gear 26. The shaft 31 may extend as indicated by the arrow thereon to a rotary position indicator of the driven tuning elements, for instance, so that a desired rotary position of the gear 26 may be selected for a corresponding stopping position of the driven apparatus.

Thus, when it is desired to stop the mechanism either in the upper or lower positions as shown in the drawing the block 27 or 28 is moved toward the center of the gear 26 by operation of the lever 16 which at the same time acts to reverse and slow down the motor 1. The reversal and slow-down of the motor as already indicated is accomplished by operation of the switch 8 which reverses the armature connections and at the same time inserts the resistance 11 into the armature circuit. As the speed of the motor is reduced the action of the centrifugal force on the weight 23 will be correspondingly lessened and the lever 21 due to the action of the spring 25 will assume the position indicated in broken lines at 24. As long as the rotation of the stopping mechanism 19 is in the direction of the arrow, the curved back surface 33 of the lever 21 will permit it to slide past the stopping blocks. As soon as, however, the rotation of the motor is reversed by means of the switch 8 the rotation of the lever 21, now in the position shown at 24, presents the surface 22 in respect to the blocks 27 and 28 in such a way as to engage them firmly. The shaft 18 will be stopped as soon as an engagement is made between the surface 22 and either of the blocks 27 and 28, the rotary position of the shaft being determined by the rotary adjustment of the gear 26. The motor remains continuously energized in the reversed direction so that the stopping mechanism may be continuously urged against the respective block regardless of what position it may be turned to by the operation of knob 30.

In Fig. 2, there is shown an alternate stopping mechanism which may take the place of that shown in Fig. 1 when, for instance, it is desired to stop the motor in only one and not in either of two given positions. In this instance the place of the stopping blocks 27 and 28 is taken by a cam member 34 which is secured to gear 26 and is provided with an indentation forming a surface 35. Fixedly mounted on the shaft 18 is shown a lever 36 at the end of which an arm 37 is pivoted at 38. The arm 37 is provided with a stopping surface 39 adapted for engagement with the surface 35 and which also carries a weighted portion indicated at 40. The arm 37 is urged toward the periphery of the cam 34 by means of a spring 41 secured to the lever 36 and the arm 37. When the shaft 18 and the lever 36 are rotated in the direction of the arrow shown on the cam at normal operational speed, the weight 40 keeps the arm 37 sufficiently far away from the peripheral surface of the cam so that it will not engage the surface 35, analogous to the action described for Fig. 1. When it is desired to stop the motor, the motor is reversed, so that a quick stop may be achieved, and energized for

slow rotation in the opposite direction until the detent at 35 and the surface 39 engage whereby the surfaces are held in contact. In the modification of Fig. 2 it is not necessary to provide a lever as shown at 16 in Fig. 1, since the operation merely of a switch corresponding to that indicated at 8 will stop the mechanism in the single given stop position.

It will be apparent from the above description that the stopping mechanism herein disclosed avoids undesired catching and jamming while preserving mechanical simplicity and at the same time provides for positive action when stoppage is desired.

While the above is a description of the principles of this invention in connection with specific apparatus, it is to be clearly understood that this description is made only by way of example and not as a limitation on the scope of this invention as defined in the accompanying claims.

I claim:

1. For use with a rotatable device which it is desired to stop at any given rotary position; a stopping system comprising shaft means for driving the device, detent means including a first member mounted on said shaft and a detent pivotally secured to said first member, stop means mounted for movement into and out of the path of said detent, means for adjusting said stop means to any predetermined rotary position, means for holding said stop means and said detent out of engagement with each other during normal operative rotation of said shaft, means normally urging to effect an engagement between said detent and said stop means, and means for controlling the rotation of said shaft, said stop means including stopping blocks radially movable with respect to said shaft, and said control means including an electric motor having speed and direction control switch means, and means for effecting simultaneous operative movement of said blocks and of said switch means.

2. For use with a device which it is desired to stop at any given rotary position, a stopping system comprising shaft means for driving the device, detent means including a first member on said shaft for rotation thereby and a second member pivoted on said first member having a detent surface, a stopping block arranged for radial movement with respect to said shaft into and out of engagement position with said detent surface, spring means between said first and second members to normally urge the latter into an engaging position, a weighted portion on said second member for holding said second member out of engagement with said block by the action of centrifugal force upon said shaft, means for selectively, rotatably, adjusting the position of said block relative to said shaft, driving means for said shaft, and a mechanism for simultaneously effecting the radial movement of said block and a reversal of said shaft.

3. For use with a device which it is desired to stop at any given rotary position, a stopping system comprising shaft means for driving the device, detent means including a first member on said shaft for rotation thereby and a second member pivoted on said first member having a detent surface, a pair of stopping blocks arranged for radial movement with respect to said shaft into and out of engagement position with said detent surface, spring means between said first and second members to normally urge

the latter into an engaging position, a weighted portion on said second member for holding said second member out of engagement with said blocks by the action of centrifugal force upon said weighted portion during normal rotation of said shaft, means for rotatably adjusting the position of said blocks relative to said shaft including gear means mounting said blocks and means for selectively adjusting the rotary position of said gear, an electric motor for driving said shaft, motor circuit control means for controlling the speed and rotary direction of said motor, and a mechanism for simultaneously effecting the radial movement of said blocks and a reversal and slow-down of said motor.

4. A stopping system for use with a rotatable device which is desired to be stopped at any given rotary position, comprising means to drive said device including a shaft, a member carried by said shaft, a detent pivotally supported on said member, a rotatable member mounted for rotation coaxially of said shaft, a stop carried by said rotatable member, means for rotatably adjusting said rotatable member, said stop being

10

5

mounted for movement radially of said rotatable member and the means to drive said device including an electric motor having a speed and direction control switch and means for effecting simultaneous operative movement of said switch and of radial adjustment of said stop.
